His Attorney.

UNITED STATES PATENT OFFICE.

CLARENCE D. LUKENS, OF ST. LOUIS, MISSOURI, ASSIGNOR TO C. DE WITT LUKENS SURGICAL MANUFACTURING COMPANY, OF ST. LOUIS, MISSOURI, A CORPORATION OF MISSOURI.

ASEPTIC LIGATING-PACKAGE.

1,334,916.

Specification of Letters Patent. Patented Mar. 23, 1920.

Application filed December 4, 1916. Serial No. 135,001.

To all whom it may concern:

Be it known that I, CLARENCE D. LUKENS, a citizen of the United States, and residing at St. Louis, in the State of Missouri, have 5 invented a certain new and useful Improvement in Aseptic Ligating-Packages, of which the following is a specification.

This invention relates to a prepared aseptic ligating package adapted for use by 10 surgeons in ligating wounds.

One of the prime conditions of a successful surgical operation is that the ligature be aseptic. This requires that the ligature be kept in such a condition that all possibility 15 of contamination, before it reaches the wound, be prevented. Accordingly, the ligature is usually furnished in a sealed tube containing an aseptic solution. Where, however, the ligature required for certain 20 operations, where many ligatures must be tied, is long, and where the ligature must be entirely removed from the tube, it is not only liable to become tangled, thereby delaying a serious operation, but is also liable 25 to become contaminated before it reaches the wound. It must be remembered that a ligature, after it has been in the aseptic solution for a period, becomes soft and is very 30 easily tangled. Moreover, it is highly desirable that kinking of the ligature be avoided as much as possible, as this breaks its fibers and reduces its efficiency.

One of the objects of this invention, therefore, is to provide a prepared aseptic ligating package, which, while it preserves the ligature in a form where its useful qualities will be conserved, at the same time delivers it in such a condition that the ligating 35 of the wound is facilitated, and the unused portion maintained aseptic and untangled.

Further objects will appear from the detail description taken in connection with the accompanying drawing, in which,

40 Figure 1 is a side elevation of the prepared aseptic ligating package embodying this invention;

Fig. 2 is a vertical section, on the line 2—2, Fig. 1;

Fig. 3 is a detail of the inner ligature carrying tube; and,

Fig. 4 is a view showing the method employed in using the tube for ligating a wound.

45 Referring to the accompanying drawing,

1 designates an outer tube, preferably constructed of glass and sealed at both ends. Arranged within this outer tube is an inner tube 2, which is shorter than the outer tube, of a diameter to fit loosely within the outer 60 tube; and closed at its bottom, but open at its top. This inner tube has near its open end a small lateral opening 3. Arranged within the inner tube is coiled a ligature 4 of catgut or any other suitable material, 65 which has one free end projecting through opening 3, the projecting end lying between the inner and outer tubes. The outer tube is partially filled with an aseptic solution 5, such as alcohol. The outer tube is provided near its open end with a ring 6, cut around so that when the ligature is to be 70 used, the tube may be readily broken.

In the preparation of this package, the ligature after being properly treated to render it sterile, is coiled within the inner tube and the open free end of this ligature is then threaded through the lateral opening. The inner tube with the ligature therein, is then slipped into the outer tube, care being 75 taken that the end will project a sufficient distance through the lateral opening, the aseptic solution added and the open end of the outer tube sealed. The ring may then 80 be cut around the outer tube in the usual manner.

In using this ligature, the outer tube is broken, turned upside down and the inner tube shaken out. The surgeon will then 85 grasp the inner tube with his left hand, as shown in Fig. 4, and using the inner tube as a reel, will unwind the ligature as the ligating proceeds, whether he uses the ligature to tie up a wound, or to thread his needles. During the entire ligating process 90 the unused ligature will remain in the tube out of contact with anything which might contaminate it, and the tube can, moreover, be used to obtain a purchase when tying a knot. On account of the construction of 100 this tube, the waste will be small, the only waste being the short end remaining in the right hand after the knot is cut off.

It will, therefore, be seen that the invention 105 accomplishes its objects. Not only is there produced a ligature which is convenient to handle during the operation, but it remains aseptic. This is due to the fact that the entire ligature, including the projecting end, is wholly inclosed in a sealed 110

tube, so that the entire ligature will be effectually sealed against contamination. By providing a lateral opening in the inner tube, not only does this inner tube provide 5 a convenient holder for the ligature during the operation, but the projecting end is always held in position where it can be readily grasped and unreeled. By leaving one end of the inner tube open, the ligature can be 10 readily placed in position, without requiring it to be kinked to such an extent as will break its fibers. By leaving the lower end closed, however, the ligature cannot unreel during the operation. It is, of course, necessary 15 to make the inner tube shorter than the outer tube, so that the flame used for sealing the outer tube will not ruin the ligature.

It is obvious that various changes may be 20 made in the details of construction without departing from the spirit of this invention.

It is, therefore, to be understood that this

invention is not to be limited to the specific construction shown and described.

Having thus described the invention, 25 what is claimed is:

A prepared aseptic ligating package comprising an outer sealed tube containing an aseptic solution, an inner tube closed at its bottom but open at its top and arranged 30 within said outer tube so as to be removable therefrom upon breaking of said outer tube, said inner tube having a lateral opening near its open end and being adapted to form a ligature reel, and a ligature arranged 35 loosely within said inner tube and wholly within said outer tube and having its end projecting through said opening, adapted to prevent unreeling of said ligature, substantially as and for the purpose set forth. 40

In testimony whereof I affix my signature this 29th day of April, 1916.

CLARENCE D. LUKENS.
